UNITED STATES PATENT OFFICE

CHARLES E. SCHULTZ, OF CHICAGO, ILLINOIS

GAS FURNACE

Application filed July 15, 1927. Serial No. 205,910.

The invention relates to a gas furnace and more particularly to a furnace adapted for use by confectioners.

The principal object of the invention is to provide in a furnace of the character set forth an improved burner construction wherein a highly efficient intermixture of fuel gas with pre-heated air under pressure is obtained with consequent increased efficiency of combustion.

Another object is to provide improved means for heating the air before it is mixed with the fuel gas.

A further object is to provide an improved arrangement of fuel jets and mixing chambers.

Other objects and advantages will be apparent in the following detailed description of a preferred embodiment of the invention which I have selected for illustration in the accompanying drawings. It will be understood however, that various changes in form, construction and arrangement may be made by those skilled in the art without departing from the spirit and scope of the invention as expressed in the appended claims.

Referring to the drawings, Figure 1 is a sectional elevation taken through the center of the apparatus.

Fig. 2 is a plan view with portions of the upper plates broken away.

Fig. 3 is a fractional elevation showing the support of the burner structure.

Fig. 4 is a fractional elevation illustrating the air conduit through the burner and its supply connection.

In the drawings the reference numerals 1 and 2 indicate respectively the outer and inner walls of an insulating drum. The walls are preferably of cylindrical form separated a substantial distance to enclose an insulating air space. The walls 1 and 2 are supported at their lower margin upon an annular base plate 3 having suitable formation to receive and secure the walls 1 and 2. The base plate 3 is supported in any suitable manner, it being shown herein to have three supporting legs 4. The upper margins of the walls 1 and 2 support a top plate 5 effecting a closure of the space between the

walls and serving as a rest for utensils being heated.

Positioned within the drum is a burner structure which is supported from the base plate 3 by means of brackets 6 suitably secured to the base plate and extending radially inward of the latter as illustrated in Fig. 3. The inner ends of the brackets 6 carry a spacer sleeve 7 upon which rests a burner casing secured thereto by means of a bolt 8 extending through the bracket and the spacer sleeve and threaded into the burner casing.

The burner casing comprises a hollow annular outer portion, indicated at 9, enclosing an annular duct 10, and from which extends inwardly a flange or web 11. The inner margin of the flange 11 supports a sub-casing 12 depending from the flange and having a centrally disposed chamber 13.

A jet cap 14 is positioned above the sub-casing 12 and supported upon the upper side of the flange 11, the jet cap forming an end closure of the enlarged upper portion of the chamber within the sub-casing 12. The jet cap 14 is provided with an annular series of jet openings 15 in the preferably cylindrical lateral periphery of the cap, the openings being formed with their axes at an angle to the radial direction from the center of the cap.

Supported upon the upper side of the annular portion 9 of the casing is a plate 16 spaced from the lower flange 11 and from the upper side of the jet cap 14 to form a chamber 17 enclosing the latter. The plate 16 is provided with a plurality of suitable openings 18 communicating with the chamber 17 between the plate and flange.

The lower portion of the sub-casing 12 supports a gas inlet fixture 19 preferably screw threaded into the bottom wall of the sub-casing and extending into the chamber 13. The inlet fixture 19 is provided with an orifice at its upper end opening into the chamber 13 and controlled by a needle valve 20, adjustably secured in the lower wall of the fixture in conventional manner, and provided with an adjusting nut 21 outwardly of the fixture. A pipe 22 leading from a supply of fuel gas (not shown) is connected to

the valve fixture 19 and is adapted to supply gas to the valve orifice.

A plurality of air inlet connections, in the present instance comprising four radially arranged pipes 23, enter the side walls of the sub-casing 12 so as to communicate with the preliminary mixing chamber 13. The pipes 23 lead upwardly at their outer ends and enter the hollow annular casing 9, the upper ends of the pipe preferably extending a substantial distance into the annular chamber or air heating duct 10 and being suitably secured thereto as by being threaded into the lower wall of the casing. Air supply connections are provided in the pipe 24 leading from a source of supply of air (not shown), the supply preferably being under moderate compression. The pipe 24 herein communicates with a pair of branches 25 which extend upwardly and enter within the chambered portion 9 through the lower wall of the casing, being suitably secured thereto as indicated in Fig. 4. For convenience in igniting the gas mixture discharged from the apertures 18, a pilot light 26 may be provided, herein illustrated as supported in the drum structure, and having connection with a constant supply of gas (not shown).

In operation, compressed air is brought to the burner through the branch connections 25 and forced through the annular duct 10 in the portion 9 of the burner casing. From the duct 10 the air is discharged through the connecting radial pipes 23 into the preliminary mixing chamber 13, where the fuel gas is admitted through the valve 19 from the gas supply line. The air and gas are partially intermixed in the chamber 13 and discharged under pressure through the angularly arranged jet openings 15 into the final mixing chamber 17, from which the combustible mixture passes through the openings in the plate 16 and is burned within the combustion chamber formed by the enclosing drum. The heat of combustion radiated to the portion 9 of the burner casing effects the heating of the air passing through the annular chamber therein to a high degree, and promotes the combustible intermixture with the fuel gas entering the sub-casing chamber 13. The discharge of the hot mixture through the slanted jet openings 15 effects a swirling movement within the chamber 17, wherein is accomplished a very thorough intermixture of the heated air and fuel gas at a temperature best suited for complete combustion above the plate 16, and the production of an intense and highly efficient flame.

It has been found that this construction materially increases the heating efficiency of a confectioner's furnace over the ordinary construction of burner heretofore in use, and effects a considerable saving of time in the cooking of confections.

I claim as my invention:

1. In apparatus of the class described, a burner casing enclosing an outer circuitous air chamber and an inner final mixing chamber, said latter chamber having discharge orifices opening therefrom, a sub-casing mounted on said burner casing and enclosing a preliminary mixing chamber, a conduit connecting said air chamber and said preliminary mixing chamber, a partition member between said preliminary mixing chamber and said final mixing chamber having spirally disposed jet orifices effecting communication between said latter chambers, means for supplying fuel gas to said preliminary chamber, and means for supplying a current of air to said air chamber.

2. In apparatus of the class described, a burner casing having an air duct in its peripheral portion and having an inwardly extending flange formed thereon, a plate mounted on said casing in spaced relation to said flange and forming a chamber therebetween, said plate having discharge orifices, a sub-casing mounted on said flange having a chamber opening toward said first mentioned chamber, a closure member between said chambers having an annular cap portion, said cap portion having a series of jet passages angularly disposed to their respective radial planes, and a conduit connecting said air duct to said sub-casing chamber.

3. A gas furnace of the class described comprising, in combination, a combustion chamber, means including a pair of substantially flat plates vertically spaced apart to form a circular and relatively shallow mixing chamber, the upper one of said plates having a plurality of discharge ports communicating with said combustion chamber, the lower one of said plates having a central opening therein, a discharge head fitting into said opening and projecting into said mixing chamber, said head having a series of spirally disposed jet orifices discharging laterally into said mixing chamber, said head further providing below said lower plate a preliminary mixing chamber, an outer circuitous air chamber disposed within the combustion chamber adapted for connection on the one hand with a source of air under pressure and on the other hand with said preliminary mixing chamber, and means connected with a source of fuel gas under pressure for discharging the same into said preliminary mixing chamber.

4. A gas furnace of the class described comprising, in combination with a combustion chamber, a burner structure providing an annular and relatively shallow mixing chamber arranged centrally within said combustion chamber and having discharge ports in its upper side communicating with the combustion chamber, means providing an annular air chamber adapted for connection

with a source of air, and a discharge head having a preliminary mixing chamber formed therein below the first mentioned mixing chamber and connected with said air chamber and also with a source of fuel gas, said discharge head having its upper end projecting into said first mixing chamber with a series of spirally disposed jet orifices discharging laterally from the head.

5 5. An apparatus of the class described including a burner structure having a circular plate with the peripheral portion shaped to provide an annular air chamber at the upper side of the plate, a second plate coacting with said annular portion to form with the first plate a circular and relatively shallow chamber, the second of said plates having a plurality of discharge ports therein, and the first plate having a central opening therein, 10 a discharge head fitting into said opening and projecting into said chamber, said head having a central portion forming a preliminary mixing chamber, and a duct connecting said annular air chamber with said preliminary 15 mixing chamber, said discharge head having a series of jet orifices discharging into said circular chamber.

20 In testimony whereof, I have hereunto affixed my signature.
